UNITED STATES PATENT OFFICE.

JOHN C. BOOTH AND SHERMAN S. SHARPLES, OF BARRE, VERMONT.

PROCESS FOR SPLITTING GRANITE, MARBLE, AND OTHER ROCKS.

Application filed May 17, 1926. Serial No. 109,803.

Figure 1 is a plan view of a block of granite or other rock which is to be split.

Fig. 2 is a view in perspective showing diagrammatically the location of the electric heating units in place, and a circuit connection therefor.

The invention is directed broadly to a process of splitting granite, marble or other rocks, which consists in drilling a series of 10 relatively small holes in the plane of desired cleavage, which holes are spaced from each other and extend well into the block which it is desired to split. The depth and size of the holes will vary according to the 15 thickness of the block which it is desired to split. A series of holes are indicated at 1, 2 and 3 in the drawings. In each hole is placed an electric unit A, which may be of any well known type. This heating unit 20 fits loosely within the hole, and all of the heating units are connected by conductors to a source of electric current, so that the units may be simultaneously heated and maintained heated until the splitting of the

rock is brought about. The heat from the 25 electric units is, of course, transmitted to the rock, and by concentrating the heat at the units and spacing the same in the plane of desired cleavage, we are able to bring about the splitting of the rock 30 very quickly and in a very efficient manner.

What we claim as new is:—

The process of splitting granite and similar rock along definite surfaces of cleavage whereby to prepare blocks of predetermined 35 size and shape, which consists in forming a series of relatively small holes spaced from one another and lying in the desired surface of cleavage, said holes being extended well into the rock, inserting in each hole an electric 40 heating unit and simultaneously heating said units and maintaining the same heated until cleavage of the rock is obtained.

In testimony whereof we affix our signatures this 8th day of May, A. D. 1926.

JOHN C. BOOTH.
SHERMAN S. SHARPLES.
